[57] CLAIM

The ornamental design for an outdoor light, as shown and described.

DESCRIPTION

FIG. 1 is a front elevational view of an outdoor light, showing my new design;

FIG. 2 is a top plan view thereof;

FIG. 3 is a fragmentary cross-sectional view thereof taken on line 3—3 of FIG. 2 on an enlarged scale;

FIG. 4 is a fragmentary cross-sectional view thereof taken on line 4—4 of FIG. 1;

FIG. 5 is a rear perspective view thereof with the housing omitted for convenience of illustration;

FIG. 6 is a rear elevational view thereof with the housing omitted for convenience of illustration;

FIG. 7 is a front elevational view thereof with the housing omitted for convenience of illustration;

FIG. 8 is a side elevational view thereof with the housing omitted for convenience of illustration; and

FIG. 9 is a bottom plan view thereof with the housing omitted for convenience of illustration.
